UNITED STATES PATENT OFFICE.

WALTER A. HOLDEN, OF ANSONIA, CONNECTICUT, ASSIGNOR TO THE ROBERT N. BASSETT COMPANY, OF SHELTON, CONNECTICUT, A CORPORATION OF CONNECTICUT.

BUCKLE.

996,248.

Specification of Letters Patent. Patented June 27, 1911.

Application filed January 18, 1909. Serial No. 472,802.

To all whom it may concern:

Be it known that I, WALTER A. HOLDEN, a citizen of the United States, residing at Ansonia, in the county of New Haven and 5 State of Connecticut, have invented a certain new and useful Improvement in Buckles, of which the following is a specification.

My invention relates to buckles of the 10 class designed to carry the extremity of a webbing and to operate along the running portion of the latter to form an adjustable loop; and its object is to provide a device of this character having a plurality of pivoted 15 members arranged to fold on each other into interlocking relation for the purpose of confining the adjustable portion of the webbing.

With this principal object in view my invention consists in the details of construction 20 and manner of operation more fully set forth in the following description and accompanying drawings in which like reference characters refer to corresponding parts.

In the drawings: Figure 1 is a front view 25 of the buckle a portion of the front and the attached webbing being shown broken away; Fig. 2, a vertical transverse section taken through the middle of Fig. 1; Fig. 3, a rear view of the buckle showing the front 30 raised; Fig. 4, a side view of the buckle in its open position; Fig. 5, a rear view of a further modification showing the front raised, and Fig. 6, a vertical section taken on line $x-x$ in Fig. 5.

Referring to Figs. 1, 2, 3 and 4 the buckle comprises an open frame A, having a web carrying member or body portion B pivotally mounted on its lower side, and a front or shield C swung from its upper side. The 40 frame A is preferably made out of a single piece of wire bent to form an opening suitable for the passage of webbing and comprises an upper side a , ends b , b and a lower side in the form of pintles c , c . The body portion or web carrying member B in this 45 particular instance is made out of a sheet metal plate having its top edge curled into a bead d and provided at its lower extremity with pintle sockets e , e in which are journaled the pintles c , c of the frame A. The lower edge of the plate B is turned up between the pintle sockets e , e to form a stop f which serves as an abutment for the adjacent ends of the pintles thereby preventing 50 relative transverse movement between the

frame A and web carrying member B. The sides of the plate B are provided at their upper extremities with laterally projecting lugs g , g which serve as stops for the ends b , b of the frame when the buckle is closed. 60 Journaled to swing on the upper side a of the frame is the front or shield C the upper edge of which is preferably curled around the frame member a to form a friction roller h . To web the buckle the same may be 65 opened as shown in Fig. 4. The free extremity i of the webbing D is first passed forwardly through the opening in the frame A and over the top d of the web carrying member B, then carried downwardly and 70 returned on itself, then passed again forwardly through the opening in the frame A and over the top d of the web carrying member B underneath the portion already threaded and is then stitched upon itself 75 below the web carrying member B forming a terminal loop in the webbing secured to or carried by the web carrying member B. The buckle webbed in this manner forms 80 an adjustable loop in the running portion of the webbing suitable for carrying a cast-off l or other attachment.

When the buckle is open, as shown in Fig. 4, the running portion may pass freely through the frame to adjust the length of 85 the loop and thereby raise and lower the cast-off l . When the buckle is closed, however, as shown in Figs. 1 and 2, the running portion of the webbing is clamped between the underside of the upper member a of the 90 frame and the top d of the web carrying member B, or to be more exact between the sleeve h incasing the top member a and that portion of the extremity i of the webbing 95 covering the top d of the web carrying member B. The running portion of the webbing is held close to the front of the buckle by the front or shield C which latter is held down in place by the frictional engagement 100 incident to the clamping action between the sleeve h and the underlying webbing. When the webbing D is under stress there is a downward pull on the web carrying member B which is taken by the pintles c , c , and an upward pull on the upper member a of the 105 frame A. The wire forming the frame A is of sufficient stiffness to resist these strains but may be of sufficient resiliency to yield slightly in closing the buckle over the webbing. This yielding action not only enables 110

the buckle to be used on webbing of varying thickness but also effects a more secure and positive clamping action. When the webbing is under stress there is a tendency 5 to turn the web carrying member B on its pivot rearwardly through the opening in the frame member A, thus the buckle will close itself when the webbing is put under stress, the stops on the web carrying member B determining the throw or relative position of these two parts. To open the buckle the front C is turned up causing the sleeve h^2 to roll rearwardly on the webbing thereby upsetting the clamping arrangement. 10 15 In the particular arrangement herein I have described the manner of holding the running portion of the webbing as resulting from a clamping action but it is obvious that my invention comprehends holding the 20 webbing by effecting an engagement between the parts unaccompanied by any clamping action, which engagement is commonly known in buckles strung in this manner as "holding by deflection." It will also 25 be observed that when the buckle is in use the back is covered with webbing and the upper and lower reaches may be disposed in vertical alinement to produce an effect styled in the trade as "rustless." 30 35 In the form of my buckle above described the running portion of the webbing is locked in its adjusted position by being engaged by a portion of the front or shield. This is not essential, however, as the engaging member may be an integral part of the frame proper, a particular example being shown in Figs. 5 and 6 in which the frame A² has its upper side a flattened to form the downwardly projecting serrated web en- 40 gaging edge a^2 . The top of the front C² is cut away to permit the front to turn on the upper side a sufficient lengths being left

on each side of the cut away portion to form the pintle straps h^2 . Otherwise this modification is of the same construction and is 45 webbed in the same manner as the form shown in Figs. 1 to 4 inclusive.

It is evident from the above disclosures that I do not regard my invention as being restricted to any specific means for fastening the running portion of the webbing, provided the three pivoted members otherwise coöperate as above pointed out; and my invention is susceptible of still further modification comprehending such broad features as fairly come within the scope of the appended claim.

Having now described my invention what I claim and desire to protect by Letters Patent is:

A buckle comprising a frame having an upper side, a lower side and an opening between them, and a web attaching member hinged to the lower side and arranged to have its top portion swing rearwardly into 65 the opening in under the upper side when the buckle is closed, combined with a webbing having its extremity folded over the top of said web attaching member and its running portion passed downwardly in back 70 of the buckle, then returned on itself passing upwardly in front of the lower side and through the opening in under the top side, and a front member hinged to the upper side and arranged to swing downwardly against 75 the front of said running portion of the webbing.

In witness whereof, I have hereunto set my hand this 14th day of January, 1909.

WALTER A. HOLDEN.
